UNITED STATES PATENT OFFICE.

NIELS PEDERSEN, OF PHILADELPHIA, PENNSYLVANIA, ASSIGNOR TO ARTHUR BROCK, JR., OF PHILADELPHIA, PENNSYLVANIA.

SPRING-MOTOR CONTROL.

1,301,968.

Specification of Letters Patent.

Patented Apr. 29, 1919.

Original application filed October 10, 1916, Serial No. 124,770. Divided and this application filed January 15, 1918, Serial No. 211,908. Renewed January 7, 1919. Serial No. 270,026.

To all whom it may concern:

Be it known that I, NIELS PEDERSEN, a citizen of the United States of America, and a resident of the city and county of Philadelphia, in the State of Pennsylvania, have invented a certain new and useful Improvement 5 in Spring-Motor Controls, of which the following is a true and exact description, reference being had to the accompanying drawings, which form a part thereof.

The general object of my present invention is to provide improved speed regulating means for a spring motor.

More specifically one object of my invention is to provide an effective speed regulating mechanism proper which by reason of its sensitiveness, reliability, form, and weight is especially adapted for use as a part of the actuating mechanism of an automatic spring 15 motor actuated camera suspended from, or otherwise flexibly mounted upon, an aeroplane or other air craft, but my improved speed regulating mechanism proper is not restricted to this particular use.

The various features of novelty which characterize my invention are pointed out with particularity in the claims annexed to and forming a part of this specification. For a better understanding of the invention, 20 however, and the advantages possessed by it, reference should be had to the accompanying drawings and descriptive matter in which I have illustrated and described preferred embodiments of my invention.

Of the drawings:

Figure 1 is an elevation of a portion of an aeroplane on which is mounted a spring motor driven camera provided with a form of my control mechanism preferred for such 25 use.

Fig. 2 is a partial sectional plan of the camera.

Fig. 3 is a side elevation of a portion of the apparatus shown in Fig. 2.

Fig. 4 is an elevation of a manually adjustable controller.

Fig. 5 is a section on the line 5—5 of Fig. 4.

Fig. 6 is a view taken similarly to Fig. 3 30 showing a modification.

Fig. 7 is a sectional plan taken on the line 7—7 of Fig. 6 and on a larger scale, and

Fig. 8 is an elevation illustrating a further modification.

In the drawings, and referring first to the construction shown in Figs. 1 to 5, inclusive, A represents the fuselage or frame work of an aeroplane provided with a seat A' for the driver and a seat A² for the observer. Mounted below the seat A' is a camera B 60 which is connected to the frame work by a universal coupling comprising gimbal frames C and D. This permits the camera to maintain to a substantial extent a fixed vertical axis notwithstanding pitching and rolling 65 movements which the air craft may experience.

It is unnecessary for an understanding of the present invention to describe the camera mechanism inclosed within the camera housing further than to say that it comprises a main actuating spring motor E, a portion of which is shown in Fig. 2, and that the speed of operation of the main motor is directly controlled by a second auxiliary 75 spring motor F or timing mechanism by means of which the cam wheels F' mounted on the spring barrel F² of the auxiliary motor are the only parts illustrated. A camera mechanism of this type is disclosed in detail 80 in the application, Serial No. 118,957, filed jointly by L. J. R. Holst and myself on September 8, 1916.

The timing mechanism or auxiliary motor F has its spring barrel F² journaled on the 85 winding shaft F³. The spiral driving spring F⁴ of the auxiliary motor F has its inner end secured to the shaft F³ and its outer end secured to the spring barrel F² in which the spring is inclosed. The spring barrel F² has 90 secured to it a spur gear F⁶ which is coaxial with the shaft F³ and in mesh with a small gear F⁷ secured to the shaft of an escapement disk or wheel F⁸. Coöoperating with the escapement wheel F⁸ is an escapement 95 anchor F⁹ carried by a rock shaft F¹⁰ to which is also secured a lever F¹¹ forming one of the elements of a compound pendulum. The lever element F¹¹ is connected at its lower end to the second element F¹² of 100

the compound pendulum by a pin and slot connection which, as shown, comprises a pin F¹³ carried by the pendulum element F¹¹ working in a radial slot formed in one side 5 of the pendulum element F¹². The pendulum element F¹² comprises a body portion in the form of a disk or fly wheel, which has a supporting shaft F¹⁶ journaled in the two forks of the bifurcated end of a lever F¹⁶.
10 The latter is supported by a shaft F¹⁷ journaled in the frame work of the auxiliary motor.

In the particular construction disclosed 15 the winding shaft F³ carries a gear F²⁰ in mesh with the gear E²⁰ forming a part of the main motor E with the result that the spring F⁴ of the auxiliary motor is normally wound up by the main motor as fast as it unwinds and thereby through the cams F' 20 permits of a corresponding movement of the main motor. The initial tension of the auxiliary motor spring F⁴ may be adjusted by means of the external knob F²³ on the shaft F³ and the pawl and ratchet connection between the shaft F³ and the gear F²⁰ formed by the pawl F²¹ secured to the gear F²⁰ and the ratchet wheel F²² secured to the shaft F³. The combination with a main motor of an auxiliary spring controlling motor having 25 its driving spring kept under tension by the main motor, while novel with me forms no part of the present invention but is disclosed and claimed in my prior application, Serial No. 95,890, filed May 6, 1916.

30 The lever F¹⁶ is angularly adjusted to thereby vary the frequency of vibration of the compound pendulum controlling the speed of the motor F by means of a cam I, the shaft I⁴ of which is journaled in the frame work of the motor F. The cam I bears at its edges against a roll F¹⁸ journaled in the adjacent end of the lever F¹⁶. The roll F¹⁸ is held against the periphery of the cam I by a spring F¹⁹. Secured to the cam 35 I and coaxial therewith is a gear wheel I' in mesh with a worm I² which is journaled in the frame work of the motor F and the stem or shaft of which is connected by the coupling I³ to a shaft section I⁵ projecting through and journaled in the housing of the camera B.

The shaft I⁵ is connected to the operating shaft G¹¹ of a manually actuated adjusting mechanism G mounted on the dash board in 40 front of the observer's seat A² or on any other convenient controller stand by a flexible transmission H which, in the form shown, comprises a plurality of shaft sections and gimbal joints H' connecting the sections to one another, and connecting the ends of this flexible connection to the shaft I⁵ and G¹¹ respectively. Conveniently one of the sections of the shaft H may comprise a length adjusting sleeve H² as shown.

The adjusting mechanism G comprises an operating arm G² carried by a shaft G⁵ and sweeping over a fixed dial G', which is provided adjacent its periphery with holes G⁴ into one or another of which is inserted the stem of an operating button G⁶ carried by the arm G² and serving, when entered in any one of the holes G⁴, to secure the arm G² in the corresponding adjustment. The shaft G⁵ is connected to the shaft G¹¹ with which it is in coaxial alignment by speed increasing gearing including a large spur gear G⁶ carried by the shaft G⁵, a small spur G⁷ in mesh with the gear G⁶ and secured to the countershaft G⁹, and a large spur gear G⁸ secured to the countershaft G⁹ and in mesh 80 with a small spur gear G¹⁰ which is secured to the end of the shaft G¹¹.

With the particular mechanism described, one complete rotation of the arm G² serves to give the cam I one complete turn, though, as shown, less than one turn of the cam I imparts the full throw to the lever F¹⁶. At the same time, the screw and worm connection provided between the shaft I⁵ and the cam I prevents any possibility of the adjustment of the cam I by the pressure exerted against it by the roll F¹⁸.

As the cam I is rotated and the pin F¹³ of the pendulum element F¹¹ is thus moved in the slot F¹⁴ toward and away from the center of the pendulum element F¹², the amplitude of the angular movement of the pendulum element F¹² necessary to accommodate the escapement releasing angular movement of the pendulum element F¹¹ increases and diminishes. The frequency of vibration of the pendulum as a whole is increased and diminished by decreasing and increasing, respectively, the amplitude of the angular movement of the pendulum element F¹². A spring F³⁰ carried by the frame work of the motor F is arranged to engage the periphery of the pendulum element F¹² and arrest the motion of the latter and thereby stop the motor F as the high point of the cam I is moved into engagement with the lever F¹⁶.

The mechanism described permits of a very sensitive, accurate and reliable control of the camera mechanism without subjecting the camera housing to torques objectionably interfering with the swinging movements of the camera relative to the frame of the aeroplane necessary to the maintenance of the optical axis of the camera parallel with itself notwithstanding the pitching and rolling movements of the aeroplane. The flexible connection between the controller stand and the camera formed by the jointed shaft H does not at any time appreciably interfere with the necessary freedom of movement of the camera relative to the supporting air craft frame work.

In Figs. 6 and 7 I have illustrated an application of speed controlling mechanism to a spring motor mechanism FA, which, as far as the present invention is concerned, 5 differs from the arrangement shown in Figs. 2 and 3 only in the following respects: In the motor FA the escapement wheel F^8 of the motor F is replaced by a worm wheel F^{80} in mesh with a worm F^{81} the lower end of 10 which rests in a step bearing carried by a bracket F^{82} forming a part of the framework of the motor FA. The shaft F^{81} carries a fan blade comprising a section F^{83} secured to the shaft F^{81} and a section F^{84} 15 axially adjustable on the shaft F^{81} and telescoping with the section F^{83} . The fan section F^{84} comprises a hub portion F^{85} which rests on the curved upper edges of the forks of a bifurcated lever F^{160} which is supported 20 and angularly adjusted just as is the lever F^{16} of the construction first described, and which differs from the lever F^{16} only in the shape of a portion of the lever engaging the hub portion F^{85} of the fan section F^{84} . 25 With the apparatus shown in Figs. 6 and 7 the effect of the angular adjustment of the lever F^{160} is to increase or diminish the effective length of the fan and thereby to increase or diminish the retarding effect 30 and thus to reduce or increase the speed of the motor FA.

In the form of speed controlling mechanism illustrated in Fig. 8, the spring motor FB proper is essentially the same as the 35 motor F shown in Figs. 2 and 3 except in the form of the compound element employed. In Fig. 8 the pendulum element F^{110} secured to the escapement anchor shaft may be substantially identical with the element F^{11} of Figs. 1, 2 and 3. The coöperating pendulum F^{120} in this form has its supporting shaft F^{121} directly journaled in the frame work of the motor FB. The pendulum element F^{120} comprises diametrically opposed arms on which are mounted 45 adjustable weights F^{122} , and comprises horns F^{123} between which is located a device F^{124} employed to directly limit the permitted range of angular movement of the pendulum element F^{120} . As shown, the element F^{124} is carried by a shaft F^{125} which also carries a worm gear F^{126} in mesh with a worm F^{127} . The shaft F^{128} carrying the worm F^{127} extends 50 through the camera housing BB or other casting inclosing the motor FB, and is connected by the coupling F^{129} to some suitable adjusting mechanism by a flexible shaft HA.

In the operation of this form of my invention the shaft F^{128} is adjusted to move 60 the member F^{124} between the full and dotted line positions shown. When the member F^{124} is in the full line position the pendulum element F^{120} is positively held against oscillation and the operation of the motor FB is

thereby arrested. When the member F^{124} is 65 in the dotted line position the motion of the pendulum element F^{120} is unrestrained and the motor FB operates at minimum speed. In intermediate positions of the member F^{124} the throw of the pendulum element 70 F^{120} is restricted with the result that the speed of the motor FB is cut down more or less accordingly as the throw of the pendulum element F^{120} is restricted less or more. The novel combination with an automatic 75 spring motor actuated camera adjustably mounted on an aeroplane of an independently supported control mechanism for regulating the operation of the camera motor disclosed, but not claimed herein, is claimed 80 in my prior application Serial No. 124,770, filed Oct. 10, 1916, of which the present application is a division.

While in accordance with the provisions of the statutes I have illustrated and described the best forms of my invention now known to me, it will be apparent to those skilled in the art that changes can be made in the form of the apparatus disclosed without departing from the spirit of my invention, and that some features of my invention may sometimes be used with advantage without a corresponding use of other features.

Having now described my invention, what I claim as new and desire to secure by Letters Patent, is:—

1. In combination a spring motor provided with an escapement release and a controlling pendulum therefor comprising two oscillating parts pivotally connected to one another and oscillating about separate axes, and means for varying the distance between said axes.

2. The combination in a spring motor provided with an escapement release, of a controlling pendulum therefor comprising two parts oscillating synchronously about separate axes, one of said axes being stationary and an adjustable element on which the other element is journaled.

3. The combination in a spring motor provided with an escapement release including an oscillating anchor, a pendulum element oscillating about an axis laterally displaced from the axis of said anchor and connected to said anchor to oscillate in synchronism therewith, and means for varying the vibration frequency of said element.

4. The combination in a spring motor provided with an escapement release including an oscillating anchor, of a pendulum element oscillating about an axis laterally displaced from the axis of said anchor and connected to said anchor to oscillate in synchronism therewith, and means for varying the amplitude of vibration of said pendulum element to thereby vary its vibration frequency.

5. The combination in a spring motor of a driving spring, a speed regulating element geared to and moved by said spring, a lever for adjusting said element to different positions to thereby vary the speed of operation of said motor, a cam for adjusting said lever and means for adjusting said cam.
6. The combination in a spring motor

provided with an escapement release including an oscillating anchor element, a second element connected to the first by a pin and slot connection, an adjustable support on which said second element is mounted to oscillate about an axis laterally displaced from the axis of oscillation of said anchor. 10

NIELS PEDERSEN.
